UNITED STATES PATENT OFFICE

CLARENCE L. WHITE, OF CUYAHOGA FALLS, OHIO, ASSIGNOR TO THE GOODYEAR TIRE
& RUBBER COMPANY, OF AKRON, OHIO, A CORPORATION OF OHIO

DESIGN FOR A SHOE SOLE

Application filed March 20, 1930. Serial No. 34,982. Term of patent 14 years.

To all whom it may concern:

Be it known that I, CLARENCE L. WHITE, a citizen of the United States, residing at Cuyahoga Falls, in the county of Summit and State of Ohio, have invented a new, original, and ornamental Design for a Shoe Sole, of which the following is a specification, reference being had to the accompanying drawings, forming part thereof.

Fig. 1 is a plan view of a shoe sole showing my new design; and

Fig. 2 is a cross-sectional view taken substantially along the line II—II of Fig. 1.

I claim:

The ornamental design for a shoe sole, as shown.

CLARENCE L. WHITE.
